UNITED STATES PATENT OFFICE

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

BIT PUNCH

Application filed October 14, 1927. Serial No. 226,135.

This invention relates to punching devices, but more particularly to punches adapted to reform the bores of hollow articles, such as drill steels in which the bore frequently becomes partially or at times wholly closed during a prior sharpening operation.

One object of the invention is to enable the punch pin to be readily freed from the article intended to be punched without the aid of special appliances for separating these elements whenever they adhere together, due to the expansive action of the heated article on the comparatively cool punch pin.

Other objects will be in part obvious and in part pointed out hereinafter.

In the accompanying drawings illustrating a practical application of the invention,

Figure 1 is a longitudinal elevation, partly in section, of a bit punch having the invention applied thereto,

Figure 2 is a view similar to Figure 1 of the front end of the bit punch showing the anvil block in retracted position and the punch pin driven into the working implement, and

Figure 3 is a view similar to Figure 2 showing the position of the anvil block for freeing the punch pin from the working implement.

Referring more particularly to the drawings, A designates a base of a bit punch having holes B for the reception of bolts (not shown) whereby said base may be clamped to a support or machine such as a drill sharpener.

The base A is provided at its rearward end with a cap C having a bore D to receive slidably a projection E carried by a back head F. The back head F forms a closure for the rearward end of a cylinder G which may be secured to the back head in any suitable manner.

Pressure fluid for actuating the bit punch may be conveyed from a suitable source of supply (not shown) through a coupling H connected in this instance to the back head F and communicating with a throttle valve J through a passage K in the back head. The throttle valve J controls the admission of pressure fluid into the distributing element

(not shown) but the position of which is indicated as at L on the side of the cylinder.

Pressure fluid distributed by the distributing element may pass to the front end of the cylinder through an inlet passage O and 55 into the rearward end of the cylinder G through an inlet passage P for actuating a piston Q in the cylinder G.

As will be observed, the projection E of the back head F is disposed slidably in the cap C. 60 Due to this arrangement the throttle valve J may be opened by manually sliding the cylinder G rearwardly. Movement of the cylinder in a forwardly direction is effected by a spring D' seated in the bore D and pressing 65 against the projection E.

The throttle valve J has a stem R which extends to a point near the rearward end of the bore D and in its open position abuts a set screw S in the rearward end of the cap C, 70 said set screw being adjustable, will enable the throttle valve J to be so adjusted as to open it to the desired degree at the most suitable point during the rearward movement of the cylinder G.

The front end of the cylinder G in this instance extends slidably into a guide sleeve T seated on the front end of the base A and preferably secured thereto by means of clamping bolts U which engage notches V in 75 the side of the guide sleeve T to hold the guide sleeve T in operative position.

Disposed in the front end of the cylinder G is a sleeve W which acts as a guide for an anvil block X having a shank Y extending 85 slidably through the bushing W into the cylinder G to receive the blows of the hammer piston Q. The front end of the anvil block X is in the form of a chuck and accordingly has a bore Z to receive a punch pin b held in 90 operative position in this instance by a pin e which engages a notch d in the shank of the punch pin b. The overhanging or punching portion e of the punch pin b is conveniently tapered to enable said punch pin to be readily driven into a drill steel f in order to reopen the bore g in said drill steel.

By tapering the punch pin b in the manner illustrated there is less likelihood of the drill steel f adhering to the punch pin due to the 100

chilling effect of the comparatively cold punch pin on the heated drill steel *f*.

In order to limit the distance which the shank *Y* of the anvil block *X* may extend into the cylinder *G*, said anvil block is provided with a collar *h* which, when the anvil block *X* is in its rearwardmost limiting position, abuts the front end of the cylinder *G* or, as in the present construction, the front end of the sleeve *W*.

Unlike the usual type of guide sleeve used for the purpose described, that in the present instance is of considerable length to permit the formation therein of a comparatively long recess *j* of such diameter as to permit of free endwise movement of the collar *h* of the anvil block *X*. The shoulder *j'* in the guide sleeve resulting from the formation of the recess *j* serves as an abutment for the front end of the cylinder. At the front end of the guide sleeve *T* is a wall *k* which acts as an abutment for the collar *h* to limit the movement of the anvil block *X* in a forwardly direction.

The mode of operation of the device, briefly described, is as follows: When a working implement *f* with a bore *g* contracted to a degree requiring reforming is pressed against the punch pin *b* with sufficient force to overcome the pressure of the spring *D'* at the rearward end of the back head *F*, the cylinder *G*, together with the anvil block *X* and the back head *F*, will be moved rearwardly a sufficient distance to unseat the throttle valve *J*. With the throttle valve *J* in the open position, pressure fluid will pass from the passage *K* through the usual passages provided for this purpose to the distributing element whereby it will be distributed to the ends of the cylinder thus causing the hammer piston *Q* to deliver rapidly repeated blows against the shank *Y* of the anvil block *X*. For the best operation of the device, the operator should maintain a substantially uniform pressure against the punch pin to hold the anvil block *X* within the range of the blows of the hammer piston as well as to hold the cylinder and back head in the rearward extreme position to assure a constant supply of pressure fluid to the cylinder *G*.

After the punch pin *b* has penetrated the drill steel *f* to the desired depth, the pressure against the punch pin may be released by the operator. In the absence of such manual pressure, the spring *D'* will immediately act to force the cylinder and back head in a forwardly direction until the front end of the cylinder may contact with the shoulder *j'* and at this point the throttle valve will be carried out of contact from the set screw *S*. With the cylinder and back head thus carried forwardly, the throttle valve *J* will be closed automatically by the

pressure fluid in the passage *K* acting thereagainst.

After the supply of pressure fluid to the cylinder *G* has been cut off, the anvil block *X* may occupy substantially the same position with respect to the cylinder which it occupies during the punching operation. As will be observed the punch pin *b* has then penetrated the work to a considerable distance. Owing to the tendency of these elements to adhere to each other, it is essential that the working implement *f* be removed from the punch pin *b* in the shortest space of time and, of course, with the least possible effort. Such removal of the working implement *f* may be accomplished in the present instance by merely pulling sharply in an outwardly direction on the working implement *f*. This will permit the anvil block *X*, the punch pin *b* and the working implement *f*, to be moved in an outwardly direction unhindered until the collar *h* strikes the wall *k*. The distance which the anvil block and the working implement may thus be moved before the collar *h* impacts against the wall will enable these parts to attain sufficient momentum to assure the invariable removal of the working implement from the punch bit without necessitating repeated forward and backward thrusts of the working implement to achieve this result.

The present invention has been found to completely eliminate the necessity of special appliances for prying the working implement from the punch pin as is so frequently necessary in similar devices in which the equivalent of the recess *j* is only of sufficient length to permit of very slight movement of the collar *h*. Moreover, owing to the fact that the present invention enables the immediate removal of the working implement *f* from the punch pin *b* after the punching operation there is little or no opportunity for the heated working implement to adhere to the punch pin *b*.

I claim:

A bit punch comprising a base, a socket in the base, a cylinder containing a reciprocable piston and having a back head adapted to extend slidably into the socket, a guide sleeve rigidly secured to the base for receiving the front end of the cylinder, a stop member on the guide sleeve cooperating with the end wall of the socket to permit limited endwise movement of the cylinder, means for introducing a supply of motive fluid into the cylinder to actuate the piston, said means being held inoperative in the forward position of the cylinder, an anvil block extending into the cylinder to receive the blows of the piston, a punch pin carried by the anvil block for reforming the bores of hollow articles, a collar on the anvil block to abut the front end of the cylinder, and an end wall on the guide sleeve to act as an abutment for the

collar for limiting forward movement of the anvil block, said anvil block having a considerably greater range of travel than the cylinder to permit the striking of the collar against the end wall with sufficient force to jar the punch pin free from the article.

5 In testimony whereof I have signed this specification.

LEWIS C. BAYLES.
